UNITED STATES PATENT OFFICE.

THOMAS K. CORLESS, OF NEW YORK, N. Y.

TURBINE.

Application filed November 2, 1922, Serial No. 598,636. Renewed June 14, 1927.

My invention relates to a turbine, and more especially to such a device having a novel form of rotor bucket wheel.

An object of the invention is the provision of a bucket which will utilize the full energy of the gases and yet will permit the gases to escape without creating a back pressure.

Another object of the invention is to so arrange the buckets with respect to the gas nozzle that a practically continuous impulse is given to the wheel.

Other objects and advantages of the invention will be apparent from the following description when taken in connection with the accompanying drawings, in which:

Figure 1 is a vertical section through the apparatus.

Figure 2 is a transverse section taken on line 2—2 of Figure 1.

Figure 3 is a fragmentary section taken through the wheel and one of the buckets.

Figure 4 is a fragmentary section taken on line 4—4 of Figure 3.

Figure 5 is a side elevation, showing the exhaust ports, and

Figure 6 is a perspective view of one of the buckets detached from the wheel.

Referring to the drawing more in detail, the numeral 1 designates a water-jacketed casing mounted on a base member 2. The casing 1 is formed of two circular sections bolted together around the periphery, and adjacent the center is provided with a plurality of laterally extending exhaust passages 3.

Extending through the center of the casing 1 is the main shaft 4 on which is carried the rotor 5. The rotor carries on its periphery a plurality of buckets 6. Six of these buckets are illustrated on the drawing, but it will, of course, be understood that this number may be increased or diminished as desired. The buckets 6 are provided with the perforated lugs 7 by means of which they are pinned to the rotor. The buckets 6 have the same curvature as the rotor 5 and have integrally formed therewith the baffle plate 8, which extends longitudinally of the bucket to a point adjacent the bottom thereof. The opposite end of the baffle plate 8 is bent on a sharper curve than the main portion thereof and carries exterior of the bucket the auxiliary baffle plate 9 having a flared end portion. The rim 10 of the rotor 5 is formed with the radially extending

grooves 11 for directing the exhaust gases toward the center of the casing, whence they may escape through the exhaust ports 3 to the atmosphere.

Also mounted on the base member 2 is the combustion chamber 12 provided with a water jacket 13, which envelops all but the forward tapered portion 14 of the chamber. An inwardly opening valve 15 is provided for admitting a mixed charge of gas and air from the carburetor; or, if desired, two valves may be provided, one for gas and the other for air.

The number 16 indicates a spark plug for exploding the gas which enters through the valve 15. The exploded gases pass through the tapered portion 14 of the combustion chamber and through the passage or nozzle 17 in the casing 1 to the buckets 6 carried by the rotor wheel. It should be here noted that after a short operation of the engine the portion 14 becomes sufficiently hot to explode the entering gases and the current to the spark plug 16 may be cut off.

Although only a single combustion chamber 12 and nozzle 17 are shown, it is not intended that the invention shall be so limited, as a plurality of such chambers is also contemplated in the practical operation of the invention.

In operation, the initial charge is exploded by the spark plug 16 and the exploded gases are forced through the nozzle 17 and impinge on the buckets 6. The expanding gases pass into the bucket to the bottom thereof and thence around the baffle plate 8. The gases are then divided by the plate 9 and directed into the passages 11 to the center of the casing 1, where they may exhaust through the ports 3. After the first explosion an action somewhat analogous to a pulsometer occurs in the chamber 12. The exploded gases passing out of the chamber 12 cause a partial vacuum which opens the valve 15 and lets in another charge, which is also exploded and impinges on the rotor buckets. By having the nozzle 17 rather long it is found that the friction of the gases against the wall and its inertia prevent any material back suction, so that the chamber 12 is almost entirely filled with a new charge after each explosion. When properly adjusted, the explosions will take place at a high frequency and will thus give a continuous impulse to the rotor 5.

While no compressor is shown in connec-

tion with the apparatus, it is, of course, obvious that one may be employed if desired.

From the foregoing description it will be seen that I have provided an extremely simple turbine which is composed of few parts and is consequently light and inexpensive in manufacture and also one in which practically the entire force of the explosion reacts on the rotor.

10. In accordance with the patent statutes, I have described what I now believe to be the best embodiment of the invention, but I do not wish to be understood thereby as limiting myself or the scope of the invention, 15 as many changes and modifications may be made without departing from the spirit of the invention; all such I aim to include in the scope of the appended claims.

What I claim as new and desire to secure 20 by Letters Patent is:

1. In a device of the class described, a shaft, a rotor on said shaft having radial passages in its rim, a plurality of elongated buckets on said rotor, baffle plates in said 25 buckets extending beyond the open ends thereof and to points adjacent the bottoms of the buckets, and means carried by said baffle plates for directing a fluid to the radial passages in the rotor rim.

2. In a device of the class described, a 30 shaft, a rotor on said shaft having radial passages in its rim, a plurality of buckets on said rotor arranged concentrically therewith, baffle plates in said buckets extending beyond the open ends thereof, each of said baffle plates having its outer end curved toward the center of the rotor, and a secondary baffle plate carried by said first mentioned plate for directing a fluid to the radial 35 passages in the rotor rim.

3. In a turbine having a rotor, a bucket open at one end and closed at the other end, a baffle plate in said bucket extending to a point adjacent the closed end of the bucket, the opposite end of the baffle plate extending beyond the open end of the bucket and curved 40 toward the center of the rotor.

4. In a turbine, a bucket open at one end and closed at the other end, a baffle plate in said bucket extending to a point adjacent 45 the closed end of the bucket; the opposite end of the baffle plate extending beyond the open end of the bucket and curved toward the center of the rotor, and a secondary baffle plate arranged to direct the gases at substantially right angles to the first mentioned baffle plate.

THOMAS K. CORLESS.
